WALL CABINET SAFE

Kiyoshi Uchida, Inanomura, Kawabegun, Hyo-
goken, Japan

Application April 15, 1936, Serial No. 74,570

3 Claims. (Cl. 194—59)

The present invention relates to a cabinet-safe consisting of a receptacle with a hinged lid which may be secured to a wall or the like by the latter in such a manner that it is in a horizontal position, when open, but is upright, when closed by swinging it upwards on hinges on its lid. It is provided with a special locking mechanism which is operated by a key in cooperation with a coin.

10 The cabinet-safe according to the invention is a most convenient one of the kind which is suited to be let out for rent in hotels, cabins on board ship, etc. When used in private, it may serve for a savings box as well.

15 In the accompanying drawings,

Fig. 1 is a sectional front view of the receptacle, when open, taken on the line A—A of Fig. 2.

Fig. 2 is a sectional side elevation of same taken on the line B—B of Fig. 1.

20 Fig. 3 is a sectional plan taken on the line C—C of Fig. 1.

Fig. 4 is a sectional elevation taken on the line E—E of Fig. 3 on an enlarged scale.

Fig. 5 is a partial sectional plan taken on the 25 line F—F of Fig. 4.

Fig. 6 is a partial plan of portion of the coin receiver, showing the same pressed forwards by a coin as shown in Fig. 5.

Fig. 7 is a plan showing a position of the receiver, when the same is moved leftwards.

Fig. 8 is an enlarged sectional side elevation taken on the line G—G of Fig. 4.

The receptacle 2 with its hinged lid 1 is held in position against the wall by securing said lid 35 by screws or the like to the latter. The receptacle 2 is divided by the partitions 24 and 12 into three chambers or compartments, namely a key room 3 L-shaped in the front part, a coin room along the left side, and another room 5 40 for keeping valuables in safety. The key room 3 provided with a locking mechanism, is tightly closed by means of cover plate 10. In the coin room there is placed a coin box 11 corresponding in shape, the top plate of said money box being provided with a key hole, so as to lock the box and to keep it in place against the partition 12.

The room 5 is furnished with a protector 6, hinged by means of a pair of pins 7 and brackets 50 8 to one side of the receptacle. In the cover plate 10 of the room 3 two holes 13 are cut adapted to receive the lugs 19 on the lid 1, when closed. Slidably mounted below said holes is a locking piece or bolt 14 which is operated by the key 16. 55 When the key 16 inserted into the key hole 15

is turned counter-clockwise, its bit engages with the lug 17 on the lower side of the locking piece and causes the latter to move toward the left. By this movement the catches 18 formed on the upper side of said piece or bolt 14 are shot into 5 the sockets 19' of the lugs 19 which project into the holes 13, when the receptacle is closed, as illustrated with chain lines in Fig. 2, when the receptacle is locked, as shown by chain lines in Fig. 4. For unlocking, the key is turned clockwise, when the key-bit meshed with the lug 17' makes the locking piece or bolt 14 to move towards the right, so that the catches are withdrawn from the sockets 19'.

There is provided on the lower side of the locking piece an L-shaped member 20, so arranged that, when said piece is found in a locked position, as shown by chain lines in Fig. 4, the lower limb of this member is quite clear of the keyhole 15, but, when the same is unlocked, it shuts off 20 the slit of the keyhole, so that in the former case the key may either freely be taken out of the latter or be introduced thereinto, but in the latter case it cannot be withdrawn.

The flexible lefthand portion of the locking 25 piece forms at its end a coin receiver 22 with a hollow groove 21, and carries a triangular lug 23 which engages with a projection 25 secured to the partition 24, in order to arrest the movement to the left of the locking piece or bolt 14 30 from its unlocked position. When, however, the left end of said piece is pushed forward, as shown in Fig. 6, the lug and the projection being disengaged, the key rod is free to move to the left. In this case a righthand movement of said key 35 rod or bolt 14 can be effected, as the lug glides on its inclined plane against the projection without engagement. Thus, without pressing forward the coin receiver, no locking can be effected, 40 while it is possible to unlock without difficulty.

The cover plate 10 is further provided with a slot or slit 26, for coins, which communicates through an inclined passage 27 with the front surface of the coin receiver. When a coin 28 is put in said slit 26 and pressed down against the spring 29 provided at the top of the inclined passage (see Fig. 8), it is arrested by the hollow groove 21 of the coin receiver. On closing the receptacle by swinging it on the lid hinges, the coin is pushed against the press 30 50 carried by the lid. In other words the press 30 enters through the slit 26, and the coin takes a position 28'. The coin receiver is thus pushed forward, whereby the lug 23 is disengaged from the projection 25. The locking piece or bolt 14 55

is now moved leftwards by means of the key 16, when the coin is caused to pass through a notch 31 communicating the inclined passage with the coin chute 32 and the coin falls down through the slits 33 and 34 provided on the partition 12 and on one side of the coin box 11 respectively into the money box.

5 It is absolutely necessary to use one piece of coin each time for locking. To open the receptacle, the key is turned clockwise, when it is kept in place and cannot be withdrawn. Thus the trouble of the key being missed, when the safe is not in use, is completely removed.

Now what I claim is:—

15 1. A cabinet-safe comprising a receptacle, a hinged lid thereon adapted to be secured to a wall, a locking mechanism between the lid and the receptacle, said receptacle being provided with a slit for receiving a coin, a presser carried by the lid, a bolt slidably mounted on the receptacle, an L-shaped extension formed on the lower

side of said bolt, a key kept in place by said extension when in an unlocked position, means for holding a coin dropped through said slit against said bolt, whereby the presser is adapted to engage the coin and move said bolt when the receptacle 5 is moved to a closed position adjacent the lid.

2. A cabinet-safe comprising a receptacle, a hinged lid adapted to be secured to a wall, a locking mechanism according to claim 1 in which said bolt has a flexible end formed with 10 a groove for receiving a coin, a fixed projection carried by the receptacle, and a lug on said bolt adapted to engage said projection.

3. A cabinet-safe comprising a receptacle, a hinged lid and a locking mechanism according 15 to claim 1, a coin-chute having a notch communicating with said coin-slit so arranged that a coin is caused to fall into said chute by a leftward movement of said bolt.
